C. H. PEDERSON.

FOUNTAIN BRUSH.

APPLICATION FILED DEC. 30, 1910.

1,042,032.

Patented Oct. 22, 1912.

UNITED STATES PATENT OFFICE.

CHRISTIAN H. PEDERSON, OF EAU CLAIRE, WISCONSIN.

FOUNTAIN-BRUSH.

1,042,032.

Specification of Letters Patent.

Patented Oct. 22, 1912.

Application filed December 30, 1910. Serial No. 600,166.

To all whom it may concern:

Be it known that I, CHRISTIAN H. PEDERSON, a subject of the King of Norway, residing at Eau Claire, in the county of Eau Claire and State of Wisconsin, have invented a new and useful Fountain-Brush, of which the following is a specification.

It is the object of this invention to provide in a simple, merchantable and inexpensive form, a receptacle adapted to contain shoe blacking and like plastic substances, the receptacle being so constituted that it may contain a dauber whereby the contents of the receptacle may be applied to the desired surface.

Another object of the invention is to provide novel means for effecting a closure of the receptacle, and to provide novel means for expanding the dauber and holding the same in place.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings:—Figure 1 is a perspective; Fig. 2 is a longitudinal section; Fig. 3 is a fragmental longitudinal section enlarged from Fig. 2; and Fig. 4 is a transverse section on the line A—B of Fig. 3.

In carrying out the invention a top 1 is provided, the same including a flat portion 2, having a central opening 3, surrounded by an outstanding funnel shaped outlet 4, cleft longitudinally as at 25 to define a plurality of tongues 26. Secured to the top 1 is a sleeve 6, the top 1 beyond the sleeve 6 being sloped as shown at 5. The elements above specified constitute the neck portion of the device.

The invention further includes a compressible receptacle 7, ordinarily a tube of tinfoil, rubber, or other yieldable material. The open end of this receptacle 7 is secured in any desired manner to the sloping portion 5 of the top 1.

A dauber, denoted generally by the numeral 8, is adapted to be inserted into the sleeve 6. This dauber 8 is fashioned into spiral form, and then inserted into the sleeve

6, the spiral construction of the dauber being clearly indicated at 9. A plug 10 is adapted to be inserted into the dauber 8 in the axis thereof. At its inner end, the plug 10 is tapered as denoted by the numeral 11, the tapered portion being adapted to register with the smaller end of the funnel shaped outlet 4, and to bend the ends of the tongues 26 outwardly as at 27, to engage the dauber 8, thereby holding the dauber in the sleeve 6. The invention further includes a cap 12, adapted to cover the dauber 8 and the exposed end of the plug 10, this cap 12 being threaded upon the sleeve 6, as denoted by the numeral 14. The threads on the sleeve 6 will coöperate with the ends 27 of the tongues 26 in holding the dauber 8 in place after the plug 10 is removed. The dauber may be made of any desired material and of any shape.

The plug 10 is employed ordinarily only in the manufacture of the device, and while the same is being shipped. After the device is in the hands of the customer, the plug 10 may be removed, and by compressing the receptacle 7 the contents thereof may be forced outwardly through the axial opening in the dauber 8, whereupon the contents of the receptacle may be spread about upon the shoe or other surface, by means of the dauber.

It is to be noted that when the dauber 8 is partially inserted into the sleeve 6, the plug 10 being inserted into the dauber, the cap 12 may be threaded upon the sleeve 6. When the cap 12 is rotated, the dauber 8 will be forced inwardly, the dauber engaging at its inner end, the funnel shaped outlet 4. The funnel shaped outlet 4 will serve to expand the dauber, and to force the same into contact with the sleeve 6, thus holding the dauber in place. Moreover, the rotation of the cap 12 will serve to advance the plug 10 into the dauber, thus bending the tongues 26, as at 27 and also expanding the dauber. The plug 10 thus coöperates with the funnel shaped outlet 4 in expanding the dauber, causing the same to engage firmly with the inner surface of the sleeve 6. Moreover, when the cap 12 is brought into place, the tapered end 11 of the plug will be seated in the smaller end of the funnel shaped outlet 4. Thus, in a single operation, the dauber 8 will be seated in place within the sleeve 6, the dauber will be expanded, and the ends 27 of the tongues 26

will be bent outwardly to engage the dauber 8.

Having thus described the invention, what is claimed is:—

- 5 A receptacle including a top having a tubular sleeve, there being an opening through the top, within the contour of the sleeve, the top being provided, about the periphery of the opening, with a plurality
- 10 of spring tongues disposed in conical form and having their free ends outwardly inclined, toward the sleeve; a dauber peripherally inclosed by the sleeve, the dauber in-

closing the tongues, and the inclined ends of the tongues being engaged in the dauber; 1 and a plug mounted in the dauber, the plug having a tapered end inserted between the inclined ends of the tongues.

In testimony that I claim the foregoing as my own, I have hereto affixed my signature in the presence of two witnesses.

CHRISTIAN H. PEDERSON.
